WELLS M. PROTZMAN, OF OSBORN, OHIO.

FLYING-MACHINE.

1,264,330.

Specification of Letters Patent. Patented Apr. 30, 1918.

Application filed August 31, 1917. Serial No. 189,202.

To all whom it may concern:

Be it known that I, WELLS M. PROTZMAN, a citizen of the United States, residing at Osborn, in the county of Green and 5 State of Ohio, have invented certain new and useful Improvements in Flying-Machines, of which the following is a specification.

This invention relates in general to flying-machines or aeroplanes, and more particularly to machines of that type which are adapted for use as aerial torpedoes.

In the operation of any of the various types of aeroplanes, or heavier-than-air 15 machines in general use, the provision of a suitable run-way is necessary, the machine being propelled some distance on the runway before it ascends or soars upward in an inclined direction. The speed or forward propelling force is an important factor 20 for retaining the machine in the air, and when ascending or navigating the air a forward movement of more or less speed is necessary. In descending the speed may 25 be reduced and the machine allowed to soar downward in an inclined direction under buoyant control of the planes.

One of the objects of the present invention is the provision of an aeroplane embodying novel features of construction 30 whereby it can be caused to ascend direct from its station in a substantially vertical direction when starting on its flight, and after attaining a predetermined height 35 caused to traverse the air in any direction, and to drop vertically if so desired.

Another object of the invention is the provision of a construction whereby the machine can be poised in the air.

40 With the above mentioned and other apparent objects in view the invention consists in the construction, combination and arrangement of parts as hereinafter described and pointed out definitely in the 45 claims, reference being had to the accompanying drawings which are made a part of the specification, and in which similar characters of reference are employed to designate similar parts.

50 In the said drawings Figure 1 is a plan view of the improved machine, more or less diagrammatic, and with certain portions broken away.

Fig. 2 is a side elevation with the wings 55 on the near side and a portion of the casting removed.

Fig. 3 is a fragmentary sectional view, on an enlarged scale, taken substantially on line 3—3 Fig. 2.

Fig. 4 is a fragmentary cross-section on 60 line 4—4 of Fig. 1.

Fig. 5 is a fragmentary vertical section substantially on line 5—5 of Fig. 1.

Fig. 6 is a side elevation of a detail of the mechanism which will be identified in 65 the following specification.

Fig. 7 is an end elevation of said mechanism, and Fig. 8 is a section on line 8—8 of Fig. 7.

The motive power, control and steering 70 mechanism are important factors in the operation of all types of machines of this character, but as the present invention has particular reference to the direct ascension and to the poising of the machine, no specific 75 construction of the said power, control, or steering elements is shown, described or claimed except broadly in combination with the mechanism which produces the result set forth.

If a machine embodying the elements of the present invention is employed as an aeroplane carrying an operator the motive power and other operating parts will be 80 designed and arranged to be controlled by said operator, while if used as an aerial torpedo the operation would be controlled by some suitable arrangement of timing mechanism such as clock-work or a wireless system. The present improvement can be 85 adapted to operative connection with motive power, control, and steering mechanism of numerous known types at present in use.

As lightness is an essential feature of all flying machines, a preferred construction 95 embodying the improvements, consists of a frame work made up of a series of aluminum body ring members 1 and 1^a connected by a series of ribs 2 and forming a cigar-shaped structure provided with suitable 100 brace members and a casing 3. The operative mechanism is confined within the said structure, and as before stated is no particular part of the present invention except in a broad sense.

105 A series of hinged planes or wings 4 are connected to opposing ribs 2 by trunnions 4^a seated in brackets 2^a which are firmly attached to the said ribs. The wings 4 are provided with inwardly extending members 110 4^b, said members on each side of the body being connected by longitudinal rods 5. A

cross bar 6 is arranged in the body member 1^a and is adapted to oscillate therein. Connected with the cross bar 6 and extending forward below the wing connecting rods 5 are rods or levers 7, said levers being tied together and spaced by a connecting member 7^a. A shaft 8 is mounted in the structure in suitable longitudinal bearings 9, said shaft being driven by any suitable motive power which may be elected to meet conditions. In the embodiment as illustrated an electric motor 10 is shown as the driving power merely for explanatory purposes. In practice a combustion engine would probably be employed.

The shaft 8 carries a worm 8^a which is in mesh with a worm gear 11, said gear being rigidly attached to a shaft mounted in suitable bearings 12 arranged above and 20 transversely to the shaft 8. Rigidly attached to the worm gear shaft at opposite ends thereof are disks 13, 13, said disks being provided with cam grooves 13^a (see Fig. 5) in their outer faces. The levers 7 are provided with members 7^b adapted to enter the cam grooves 13^a and be operated upon by said grooves in the revolutions of the disks and thereby raise and lower the free ends of the levers 7, said levers 25 being fulcrumed in the oscillating member 6. Adjustable clips 14 are provided for connecting the rods 5 with the levers 7. These clips are adapted to slide longitudinally on the rods 5 and are provided with 30 vertically adjustable hook members 15 which engage the levers 7, as best shown in Figs. 4 and 5. It will readily be seen that the upward and downward movement of the levers 7 will cause the wings 4 to oscillate 35 on their trunnions through the clip connections of the rods 5 and levers 7, and that the degree of oscillation is governed by the distance of the clips from the fulcrum member 6. The greater the distance between 40 the fulcrum 6 and the clips 14 the greater the degree of oscillation, and vice versa.

The wings 4 are provided with openings 4^a and have closure members or flaps 16 hinged thereto, said flaps being adapted to 45 cover said openings. As the wings oscillate upward the flaps open removing the air pressure, and as the wings oscillate downward the said flaps are closed and a continuous surface upon which the air pressure is exerted, is presented.

Rods 17 are flexibly connected with the flaps 16, as shown at 16^a. These rods extend to the interior of the structure and pass through universally adjustable holders or 60 friction members 18. The function of these rods and friction members is to stabilize the flaps in their opening and closing operations. In the embodiment as illustrated the devices 18 consist of a two-part ball 19 con- 65 fined in a socket in which it is adapted to

operate. The socket is constructed in two parts 20 and 20^a connected through flanges 20^b. The member 20 is provided with a foot 20^c for attachment to the frame of the machine, and the member 20^a is provided with a barrel 20^d in which is a spring 21 that operates on a member 22 bearing on the ball 19. The tension of the spring, and through said tension the friction of the ball 19 on the rod 17 is regulated by a screw 23. 75

The propeller 24 may be connected with the driving shaft 8 by suitable clutch mechanism, not shown, so that it can be operated simultaneously with the wings or independent thereof. Suitable steering mechanism, 80 timed controlling mechanism, and motive power connections may be installed and adapted to coöperate with the elements described.

When the machine is used as an aerial torpedo, the high power explosives are stored in a forward compartment 3^a, and when used as a passenger carrying aeroplane, suitable provision is made for the accommodation of the operator; and the operative mechanism is constructed to meet the differing conditions or uses, while the construction of the wings and their operative mechanism in all cases remains substantially as herein described and definitely set forth 95 in the claims which govern the scope of the invention.

What I claim and desire to secure by Letters Patent is.

1. In a flying machine the combination 100 of a body; plane wings hinged to said body on opposing sides thereof and adapted to oscillate on their hinges, said wings being provided with openings; closure members for the openings in the wings hinged to said wings and adapted to open and close by air pressure in the oscillation of said wings; connecting rods between the wings on each side of the machine; levers fulcrumed in the body; means for oscillating said levers; connecting members between said levers and the wing connecting rods, whereby the oscillating movement of the levers imparts oscillation to the wings. 105

2. In a flying machine the combination of 110 a body; a series of wings hinged to said body on opposite sides thereof, said wings being provided with openings; closure members for the openings in the wings, hinged to said wings and adapted to open and close 115 by air pressure in the oscillation of said wings; connecting rods between the wings on each side of the machine; levers fulcrumed in the body; cams for oscillating said levers; connecting means between said levers and the wings whereby the oscillating movement of the levers imparts oscillation to the wings; and means for operating said cams. 120

3. In a flying machine the combination of 130

a body; a series of wings hinged to said body on opposite sides thereof, said wings being provided with openings; closure members for the openings in the wings, hinged to said wings and adapted to open and close by air pressure in the oscillation of said wings; connecting rods between the wings on each side of the machine; levers fulcrumed in the body; cams for oscillating said levers; adjustable connecting means between said levers and the wings, whereby the oscillating movement of the levers imparts oscillation to the wings; and means for operating said cams.

10 4. In a flying machine the combination of a body; wings hinged to said body on opposite sides thereof, said wings being provided with openings; closure members for the openings in the wings, hinged to said wings and adapted to open and close by air pressure in the upward and downward oscillation, respectively, of said wings; connecting rods between the wings on each side of the machine; levers fulcrumed in the body; cams for oscillating said levers; adjustable connecting means between said levers and the wings, whereby the oscillating movement of the levers oscillates the wings; gears arranged to operate the cams; and means for driving said gears.

20 5. In a flying machine the combination of a body; wings hinged to said body on opposite sides thereof, said wings being provided with openings; closure members for the openings in the wings, hinged to said wings and adapted to open and close by air pressure in the upward and downward oscillation, respectively, of said wings; connecting rods between the wings on each side of the machine; levers fulcrumed in the body; cams for oscillating said levers; adjustable connecting means between said levers and the wings, whereby the oscillating movement of the levers oscillates the wings; gears arranged to operate the cams; and means for driving said gears.

25 6. In a flying machine the combination of a body; wings hinged to said body on opposite sides thereof, said wings being provided with openings; closure members for the openings in the wings, hinged to said wings and adapted to open and close by air pressure in the upward and downward oscillation, respectively, of said wings; connecting rods between the wings on each side of the machine; levers fulcrumed in the body; cams for oscillating said levers; adjustable connecting means between said levers and the wings, whereby the oscillating movement of the levers oscillates the wings; gears arranged to operate the cams; and means for driving said gears.

30 7. In a flying machine the combination of a body; wings hinged to said body on opposite sides thereof, said wings being provided with openings; closure members for the openings in the wings, hinged to said wings and adapted to open and close by air pressure in the upward and downward oscillation, respectively, of said wings; connecting rods between the wings on each side of the machine; levers fulcrumed in the body; cams for oscillating said levers; adjustable connecting means between said levers and the wings, whereby the oscillating movement of the levers oscillates the wings; gears arranged to operate the cams; and means for driving said gears.

35 8. In a flying machine the combination of a body; wings hinged to said body on opposite sides thereof, said wings being provided with openings; closure members for the openings in the wings, hinged to said wings and adapted to open and close by air pressure in the upward and downward oscillation, respectively, of said wings; connecting rods between the wings on each side of the machine; levers fulcrumed in the body; cams for oscillating said levers; adjustable connecting means between said levers and the wings, whereby the oscillating movement of the levers oscillates the wings; gears arranged to operate the cams; and means for driving said gears.

40 9. In a flying machine the combination of a body; wings hinged to said body on opposite sides thereof, said wings being provided with openings; closure members for the openings in the wings, hinged to said wings and adapted to open and close by air pressure in the upward and downward oscillation, respectively, of said wings; connecting rods between the wings on each side of the machine; levers fulcrumed in the body; cams for oscillating said levers; adjustable connecting means between said levers and the wings, whereby the oscillating movement of the levers oscillates the wings; gears arranged to operate the cams; and means for driving said gears.

vers and the wings, whereby the oscillating movement of the levers oscillates the wings; a worm gear connected with the cams for driving said cams; a worm member in mesh with the worm gear; a driving shaft connected with said worm; and means for driving said shaft.

6. A flying machine having wings hinged to the body thereof and adapted to oscillate on their hinges, said wings being provided with openings, flaps hinged to said wings for covering the openings therein, said flaps being adapted to open automatically on the upward movement of the wings and to close against the under side of the wings on the downward movements of said wings, stabilizing rods connected with the flap members, said rods extending to the body of the machine and slidable in friction members attached to said body, and means for oscillating the wings.

7. A flying machine having wings hinged to the body thereof and adapted to oscillate on their hinges, said wings being provided with openings, flaps hinged to said wings for covering the openings therein, said flaps being adapted to open automatically on the upward movement of the wings and to close against the under side of the wings on the downward movement of said wings, stabilizing rods connected with the flap members, said rods extending to the body of the machine and slidable in universally adjustable friction members attached to said body, and means for oscillating the wings.

In testimony whereof I affix my signature in the presence of two witnesses.
